UNITED STATES PATENT OFFICE.

HAMILTON D. GUFFEY, OF UNIONVILLE, MISSOURI.

FENCE TOOL.

Application filed April 5, 1923. Serial No. 630,082.

To all whom it may concern:

Be it known that HAMILTON D. GUFFEY, a citizen of the United States of America, residing at Unionville, in the county of Putnam and State of Missouri, has invented new and useful Improvements in Fence Tools, of which the following is a specification.

The object of the invention is to provide simple and efficient means for facilitating the stringing or running of fence wires, of the type requiring stretching or placement under tension, particularly when the line of the fence traverses an uneven, undulatory or hilly surface at a substantially uniform distance from the surface of the ground; and with this object in view the invention consists in a construction and combination of parts of which a preferred embodiment is shown in the accompanying drawings, wherein:—

Figure 1 is a view of a section of a fence showing a plurality of wire positioning tools or devices embodying the invention applied to the posts in the operative position.

Figure 2 is an enlarged detail view of the device detached from the post and showing the method of applying a strand fastening staple in securing the wire or strand to the post.

Figure 3 is an edge view of the device.

The difficulty in running or stretching the strands of a wire fence in order to secure the proper relation in elevation thereof above the surface of the ground while applying the required tension thereto, particularly where the surface of the ground is broken by comparatively short elevations and depressions involving distances of only one or two panel lengths, is well recognized and the conventional method of meeting the difficulty is to stretch the runner in short lengths as nearly as possible in conformity with the successive rising and falling portions of the land surface with obviously an expenditure of an amount of time which is far in excess of that required in running the fence over a comparatively level country.

In order to avoid this inconvenience and loss of time and permit of the stretching of the strands in long lengths or through considerable distances regardless of the fact that intermediate portions thereof may traverse broken or hilly or uneven surfaces, there is employed a device which in accord-

ance with the invention constitutes a wire or strand guide and consists in the form illustrated of a plate 10 provided with means for attachment temporarily to a fence post as for example the chains 11 having pins 12 and hooks 13 or the equivalents thereof for engagement with the post. Carried by the plate are upper and lower guide rollers 14, in contact with the inner side of either of which the barbed or plain fence wire or strand 15 may be arranged and between which said wire or strand is run to the end that it may engage either the upper or lower guide roller according to the direction of run and strain of the adjacent portions of the wire or strand. One of these guiding devices is applied to each of the posts located at the lowermost and uppermost portions of inclined land surfaces as indicated in Figure 1 and obviously the wire strand or runner extending between the upper and lower guides bears against one or the other according to whether the adjacent portions of the strand incline upwardly or downwardly. The intermediate portions of the strands obviously intersect the intermediate posts in substantially proper relations thereto for stapling or other fastening purposes. The guide rollers are preferably provided with peripheral projections 16 arranged in spaced relation to form bearing points for the wire strands or runners, and between the guide rollers there is arranged an opening 17 having in its periphery the throats 18 communicating with the opening and disposed radially to the guide rollers, so as to be spanned by the wire strand or runner traversing one of said rollers. This arrangement provides for placing a wire securing staple 19 in straddling relation with the strand or runner in the throat spanned thereby without interfering with the guide roller after the strand or runner has been tensioned to the desired extent. To provide for spacing the device from the post to which it is attached, the opening 17 in the plate 10 is bounded by the inturned flanges 20 disposed on diametrically opposite sides of the opening and extending from one throat 18 to the other. These flanges seat against the post and space the device therefrom to provide for the free movement of the runners between the device and the post by which it is carried. After the stapling of the runner the guid-

ing device may be removed without disturbing the runner. It will be understood that the runners in connection with which the guiding device may be utilized may either be of the barbed or plain type and that any suitable form of stretching means may be used to tension the runner after the guiding devices have been positioned and the runner has been extended through the same. It will also be understood that after the strand has been properly tensioned the stapling thereof through the intermediate posts may be effected in the usual manner before releasing the stretching means or removing the guide devices from the posts.

Having described the invention, what is claimed as new and useful is:—

1. A runner guiding device for use in wire fence building having a base for attachment to a fence post and carrying a runner guiding element, provided with projections for spacing the runner therefrom, the base having a staple receiving throat with reference to which the runner is held in spanning relation.

2. A device for the purpose described having a base provided with means for temporary engagement with a fence post, and rotary upper and lower runner guides

carried by said plate, the latter being provided between the guides with an opening having throats adapted to be spanned by a runner engaging one of the guides.

3. A device for the purpose described having a base provided with means for temporary engagement with a fence post, and rotary upper and lower runner guides carried by said plate, the latter being provided between the guides with an opening having throats adapted to be spanned by a runner engaging one of the guides, said guide being provided with spaced peripheral projections for engagement with the runner.

4. A device for the purpose described having a base provided with means for temporary engagement with a fence post, and rotary upper and lower runner guides carried by said plate, the latter being provided between the guides with an opening having throats adapted to be spanned by a runner engaging one of the guides, said guide being provided with spaced peripheral projections for engagement with the runner, said post engaging means consisting of chains provided with terminal shackle pins and hooks.

In testimony whereof he affixes his signature.

HAMILTON D. GUFFEY.
